(57) **CLAIM**

The ornamental Design for a tire sidewall, as shown and described.

DESCRIPTION

FIG. 1 is a perspective view of a tire sidewall showing my new design;

FIG. 2 is a front elevational view thereof;

FIG. 3 is an enlarged fragmentary view of the area circled in FIG. 1;

FIG. 4 is another perspective view of a tire sidewall showing the opposite side of the tire sidewall of FIG. 1 with the tire of FIG. 1 rotated about a vertical axis 180 degrees; and, FIG. 5 is a front elevational view thereof.

In the drawings, the broken lines showing of the tire tread, inner bead and the peripheral boundary between the tire tread and the sidewall depict environmental subject matter and form no part of the claimed design.
